UNITED STATES PATENT OFFICE.

CARL M. PAGE, OF CHICAGO, ILLINOIS, ASSIGNOR TO GEORGE FABYAN, OF GENEVA, ILLINOIS.

HIGH-FREQUENCY IGNITION SYSTEM.

Application filed June 1, 1920. Serial No. 385,448.

To all whom it may concern:

Be it known that I, CARL M. PAGE, a citizen of the United States, and a resident of the city of Chicago, in the county of Cook and State of Illinois, have invented certain new and useful Improvements in a High-Frequency Ignition System; and I do hereby declare that the following is a full, clear, and exact description of the same, reference being had to the accompanying drawings, and to the numerals of reference marked thereon, which form a part of this specification.

This invention relates to an improved high frequency ignition system and provides means whereby the improved high frequency oscillating current ignition system shown and described in my copending application Serial No. 381,795 filed May 17, 1920, may be adapted to existing types of internal combustion engines.

On account of the comparatively low grade fuel which is of necessity being used at the present time, it is especially desirable that means be provided for efficiently igniting mixtures thereof in the combustion chambers of internal combustion engines. Also, in view of the increasing scarcity of suitable fuel, it is desirable that the fuel be utilized in such a manner as to obtain a maximum energy therefrom. Former electrical ignition systems have utilized a current having a frequency of from a few hundred to a few thousand cycles per second, while the ignition system proposed by this invention utilizes an oscillating current of extremely high frequency which may reach a maximum of several million cycles per second and which produces an improved spark which is disruptive in character and which adds greatly to the efficiency of the engine on account of the complete ignition of fuel mixture which results therefrom.

It is an object of this invention to provide an ignition device containing concentrated inductance and capacity adapted to be connected in an ignition system to so produce an oscillating current of high frequency and a disruptive spark therein.

It is another object of this invention to provide an ignition device adapted to control the large quantities of energy necessary for the complete ignition of heavy liquid fuels without damage to the electrodes thereof.

It is another object of this invention to provide an improved device adapted to be connected in an ignition system for producing a high frequency oscillating current and a disruptive spark.

It is further an object of this invention to provide a device whereby atomized fuel may be introduced into the combustion chamber of an internal combustion engine and ignited by a spark discharge effected by an oscillating current of high frequency.

It is an important object of this invention to provide a device adapted to be applied to existing types of internal combustion engines for producing an oscillating high frequency current and a disruptive spark in the ignition systems thereof.

Other and further important objects of this invention will be apparent from the disclosures in the specification and the accompanying drawings.

The invention (in a preferred form) is shown in the drawings and hereinafter more fully described.

On the drawings:

Figure 1 is a central vertical section through an improved igniting device embodying the principles of this invention.

Figure 2 is a central vertical section through another form of igniting device.

Figure 3 is a central vertical section through an igniting device of another form.

Figure 4 is a central vertical section through an igniting device of the type shown in Figure 3, showing a different arrangement of concentrated inductance and capacity.

Figure 5 is a diagrammatic view showing the igniting device of the type shown in Figure 1 as used in the ignition system of an internal combustion engine.

Figure 6 is a diagrammatic view showing

an igniting device of the type shown in Figures 2, 3 and 4 as used in the ignition system of an internal combustion engine.

As shown on the drawings:

- 5 The form of device shown in Figure 1 is adapted to be engaged in a threaded aperture in the wall 1 of the combustion chamber of an internal combustion engine and comprises a hollow sleeve 2, which is provided
 10 with a flange 3 adapted to engage the outside of said casing 1, a chamber 4 in the lower portion thereof, and an internal peripheral flange 5, which is adapted to support an enlarged portion of a tubular insula-
 15 tor 6, which may be of porcelain, mica or other suitable material. Said insulator 6 is secured in position inside the sleeve 2 by means of a packing nut 7, which is engaged in threads in the upper portion of the tubu-
 20 lar casing 2. The insulator 6 is provided with an axial aperture and engaged in said aperture is a metallic electrode 8, which is provided with an enlargement 9 in the chamber 4 adjacent the inner end of said electrode 6, and a spirally formed portion 10, which terminates in a horizontal portion 11, which is positioned so that the end thereof is opposite the end of a second electrode 12, which is secured in the lower end of the
 25 tubular casing 2 and connected with ground through the casing 1. A suitable binding nut 13 is engaged on a threaded portion 14 of the electrode 8 in order that an electrical conductor may be connected thereto.
- 30 Figure 5 shows a circuit whereby the device shown in Figure 1 is adapted for use in the ignition system of an internal combustion engine in order to produce a high frequency oscillating current therein and to produce a disruptive spark discharge across the gap between the electrodes 11 and 12. Said circuit comprises a source of electrical energy 15, which may comprise a storage battery or an electric machine and one terminal of which is grounded at G¹, the other terminal thereof being connected through a switch 16 to one low tension terminal of an induction coil 17. The other terminal of said induction coil 17 is connected by means of a conductor 18 with a commutator 19, and intermittently through said commutator the circuit is connected to ground G². The high tension terminal of said induction coil 17 is connected by means of a conductor 20 to the common point of a distributor 21, and from said common point of the distributor 21 the circuit is selectively completed through conductors 22 and 23, which are connected to the terminals of the electrodes 8 across the spark gaps between the electrodes 11 and 12 to ground at G³. As is apparent from the drawings, the device shown in Figure 1 contains certain quantities of

concentrated inductance and capacity. The 65 inductance is represented by the spiral 10 in the lower end of the electrode 8, while the capacity is provided by the condenser formed by the enlarged portion 9 of the electrode 8, and the inner wall of the chamber 4, which, of course, has a dielectric of air or gas therebetween. The effective capacity of this condenser is considerably enhanced on account of the fact that the pressure inside the chamber at the time of spark 75 discharge is considerably higher than atmospheric.

Figure 2 illustrates another form of the device of this invention whereby concentrated inductance and capacity in the 80 proper portions may be introduced into an ignition circuit to cause an oscillating current of high frequency to flow therein. Said device is mounted on a flange 24, which is adapted to be bolted over an aperture in 85 the wall 25 of the combustion chamber of an internal combustion engine. Said flange 24 is provided with a pair of oppositely positioned apertures each of which is reduced at its inner portion to receive an insulator 26 of porcelain or other suitable insulating material engaged therethrough having an enlarged portion seated on the outer side of said restricted portion and secured thereon by a packing nut 26^a. The 90 insulators 26 are provided with axial apertures through which are engaged electrodes 27 and 28, which protrude from the inner and outer ends of the insulator. The outer ends of said electrodes are provided with 100 terminals adapted to have electrical conductors connected thereto. Secured to the inner ends of said electrodes 27 and 28 are separated horizontal plates 29 and 30, which are enclosed by a porcelain cup 31, which 105 is provided with a plurality of apertures 32, whereby the internal and external pressure on the cup are equalized. The lower end of the electrode 28 protrudes through the bottom of the cup 31 and is formed into 110 an helix 33, which is preferably enclosed in insulating material such as a block or porcelain 34, and the outer end 35 of which extends horizontally from said porcelain block. The electrode 27 extends downwardly through the cup 31 and is bent horizontally so that the end thereof is spaced from and positioned opposite the end of said horizontal portion 35, forming a spark gap therebetween. It is thus apparent that 115 the device shown in Figure 2 also provides concentrated inductance and capacity, the inductance being provided by the helix 33, while the separated plates 29 and 30 with the dielectric of high pressure air or gas 120 therebetween form a condenser affording the necessary concentrated capacity in the circuit.

Figure 3 illustrates a modification of a device of the type shown in Figure 2, in which the necessary concentrated capacity is furnished by a condenser 36, which is enclosed in a suitable container 37 and which is connected between the electrodes 27 and 28 at the outer ends thereof. The necessary concentrated inductance is provided in the device shown in Figure 3 by a helix 38, which is formed in the electrode 28 inside the insulator 26. A suitable spark gap is formed between the horizontal portions 39 and 40 of the inner ends of the electrodes 27 and 28.

The device illustrated in Figure 4 shows another arrangement of concentrated inductance and capacity. In this case a container 41 contains condensers 42 and 43 and inductance 44 connected between the outer ends of the electrodes 27 and 28 as shown. The spark gap in this case is provided between the inner horizontal portions 39 and 40 of the electrodes 27 and 28.

As shown in Figure 4, one of the electrodes 28 may be of tubular construction whereby liquid fuel may be introduced through the passage 55 therein from fuel pumping means outside the engine, connection with the outer end of said electrode being made with an insulating coupling of any well-known type. It is preferable of course, when this construction is used, to form an atomizing nozzle at the inner end 56 of the passage 55. This construction provides convenient means whereby the fuel to be ignited is sprayed directly into the path of spark discharge and since said discharge is of a disruptive character there is no danger of the electrodes becoming fouled.

Figure 6 shows a circuit whereby the ignition devices shown in Figures 2, 3 and 4 are adapted for use in internal combustion engines. Said circuit comprises a source of electrical energy 45, such as a storage battery or an electric machine, one terminal of which is connected through switch 46 with one of the low tension terminals of an induction coil 47. The other low tension terminal of the induction coil 47 is connected by means of a conductor 48 with a point 49 on a timer 50, and said point 49 is adapted to be connected through the rotating arm of the timer with the central point 51 thereof, which in turn is connected with the other terminal of the source of electrical energy 45 through conductor 52. The high tension terminal of said induction coil 47 is connected by means of a conductor 53 with the outer end of the electrode 27 and the circuit is completed across the spark gap formed between the horizontal portions 39 and 40 of the electrodes 27 and 28, cut through the electrode 28 and the conductor 54 which is connected to the conductor 52, as shown.

On account of the concentrated inductance and capacity which is self-contained in the devices shown in Figures 2, 3 and 4, the current flowing in the high tension circuit of this system is of an oscillatory character and of extremely high frequency, and the spark discharge produced thereby is disruptive and acts to efficiently ignite the fuel mixture in the combustion chamber of the engine.

As will be apparent from the foregoing description, the devices of this invention readily make possible the convenient adaptation of existing types of internal combustion engines for use with a high frequency oscillating current ignition system. The device of this invention may be readily used either in the ordinary types of internal combustion engines or in any of the heavy oil engines as, for example, the semi-Diesel type. Due to the oscillating high frequency current by which spark discharge is produced, it is possible to utilize the large amount of energy necessary for efficient ignition in the heavy fuel oil engines. This has been impractical in prior devices due to the rapid destruction of the electrodes by the comparatively low frequency current. On account of the superior ignition provided thereby, the device of this invention adds greatly to the efficiency of any engine wherein a fuel mixture is ignited in the combustion chamber.

I am aware that numerous details of construction may be varied through a wide range without departing from the principles of this invention, and I therefore do not pur-pose limiting the patent granted otherwise than necessitated by the prior art.

I claim as my invention:

1. The combination with an internal combustion engine and the ignition system thereof, of insulated electrodes electrically connected with the ignition system and extending into the combustion chamber of the engine, means providing concentrated inductance associated with the electrodes, and a condenser associated with the electrodes and inside the combustion chamber.

2. The combination with an internal combustion engine and the ignition system thereof, of insulated electrodes electrically connected with the ignition system and extending into the combustion chamber of the engine, means providing concentrated inductance associated with the electrodes, and an enclosed condenser inside the combustion chamber and connected with the electrodes.

3. In an ignition system for an internal combustion engine a circuit including a spark gap and a condenser both located within the combustion chamber.

4. The combination with an internal combustion engine and the ignition system thereof, of a pair of insulated electrodes electrically connected with the ignition system and

extending into the combustion chamber of the engine, means providing concentrated inductance associated with the electrodes, a condenser, one element of the condenser being connected to one electrode and the other element thereof to the other electrode, and an enclosure for said condenser having holes communicating with the interior of the combustion chamber.

10 5. In an ignition system for an internal combustion engine, a circuit including a

spark gap and an inductance, both located within the combustion chamber of said engine.

In testimony whereof I have hereunto subscribed my name in the presence of two subscribing witnesses. 15
